UNITED STATES PATENT OFFICE.

ERNST VOGEL, OF STOCKERAU, AUSTRIA.

SWITCHING APPARATUS FOR PUMPING PLANTS COMPRISING A PLURALITY OF ELECTRICALLY-OPERATED PUMPS.

Application filed April 4, 1925, Serial No. 20,369, and in Austria March 7, 1924.

Arrangements are already known for operating pumping plants comprising two or more pumps having different discharge volumes and for the most part also different resistance heads in such a manner that one of these pumps, which corresponds to the water-consumption for the time being and to the associated resistance head is set in operation by hand or automatically and the pump that has previously been in operation for a smaller or greater water-consumption and a corresponding resistance head is thrown out of operation.

In the case of the arrangement hitherto known the disconnecting of one pump and the starting of a second are effected one after the other in point of time, so that during the changing over, even though only for a short time, no pump is operative. From this there arise various disadvantages, for example a fall of pressure in the common air vessel, and so forth.

This invention relates to switching apparatus whereby the starting and cutting out of the pumps in question are effected simultaneously.

In the drawing, Figures 1 and 2 show one constructional form of the switching apparatus in two different positions, for example for four pumps, and Figure 3 a hydraulic controlling piston serving to actuate the switching apparatus automatically, in a central vertical section.

In Figures 1 and 2 the conductors a_1 , a_2 , b_1 , b_2 and c_1 , c_2 , leading to the electric pump-driving motors 21, 22 and 23 respectively, each comprise two contacts 30 and 31, with lever-like switches 32 and 33. The conductor d_1 , d_2 leading to the last motor 24, on the contrary, comprises only one contact 31, with a switch 33. Each two of these switches, belonging to two adjacent circuits, are connected with one another by arms 33' and 32' and a link or guide rod 34 in such a way that they always take up opposite positions, that is to say that one switch is opened if the second switch is closed. The one switch 33 of the first motor 21 remains over as an uncoupled switch.

The coupled switches and the single switch, for the successive actuation thereof, are provided with a device consisting of a fork 35. These forks are subject to the action of the stops 36, 37, 38 and 39 on a

switching rod 40. This rod can be shifted 55 backwards and forwards from point to point in its longitudinal direction within four positions.

In the case of the position shown in Figure 1 the pump motor 21 is switched on for the smallest water-consumption, because both switches 32, 33 close the circuit a_1 , a_2 . The switch 32 was closed already and the switch 33 became closed owing to the action of the stop 36 on the fork 35. All the remaining circuits are interrupted at one point and therefore the pump motors in connection therewith are switched off.

If the consumption of water rises, a longitudinal displacement of the rod 40 in the direction of the arrow is effected. The next stop 37 then acts on the associated fork 35, whereby the switch 33 of the circuit for the pump 22 is moved into the closed position, and at the same time the switch 32 of the pump 21, which is coupled thereto, is moved into the open position (Figure 2). The pump 21 is therefore cut out and at the same time the pump 22 is started, the latter result being on account of the fact that its second switch 32 is in the closed position.

Upon the consumption of water rising further the stop 38 acts on the associated fork 35, whereby the pump 22 is cut out and the pump 23 is simultaneously started.

Upon a still further increase in the water-consumption the pump 23 is cut out by the stop 39 and the largest pump 24 is started by rocking the single switch 33 into the contact 90 position.

If on the other hand, at any switching position, the consumption of water falls off, for example with the pump 22 switched on (Figure 2), the switching rod 40 is shifted 95 in the direction opposite to the arrow and by the stop 37 the pump 22 is switched off but the pump 21 is switched on.

The member 40 of this switching apparatus may be adjusted either by hand or automatically. The automatic adjustment may be effected by any suitable means, subjected to the action of the varying water-consumption. As such means there may come into consideration hydraulic regulating pistons, which are actuated by the varying quantity of the water flowing away from the common air vessel of the pumps into the consumption

network per unit of time, or pressure gauges on the said air vessel, or floats in the air vessel.

In Figure 3 is illustrated a hydraulic control piston in a duplicated arrangement serving for the adjustment of the controlling organ 40.

In each cylindrical tube *c*, which is preferably conical at the bottom, a displacer or regulator piston *d* is movably arranged, which only leaves a small gap open at its periphery for the passage of water. The regulator piston preferably forms a hollow body, which tapers off towards both ends, 15 is open on one end face, and is guided in the tube *c* by means of the longitudinal ribs *d'* occupying the central part of its length. At the bottom of each hollow body *d* is fastened a bolt *d'''*, to which at *d''* a link or 20 guide rod *e'* is attached in each case. These links lead to a double-armed lever *l* mounted fast on the control shaft *m*. The control shaft emerges from the pipe bend *n* connecting the two tubes *c*, *c* through a stuffing 25 box, and carries at its free end a weighted lever *x*.

The water passes out of the air vessel (not shown) which is common to all the pumps, into the casing, passes both displacers *d*, in the gap of which an increase 30 in velocity occurs, and flows at *b* into the consumption mains. In correspondence with this increased velocity there is in front of each piston, relatively to the direction of 35 motion of the water, a higher pressure acting than behind the piston, which, in the case of the minimum quantity flowing, is so small that the weight lever *x* and the displacer *d* occupy the position I. With an increase 40 in the volume flowing through, however, the regulator pistons adjust themselves into the positions II, III, and IV in succession, the weighted lever *x* accordingly takes up in succession the positions II, III and 45 IV and consequently opposes to the increasing pressure in front of the piston a correspondingly increasing opposing torque, whereby the pistons *d* are held in the corresponding positions. Owing to this the 50 control lever *p* which is mounted fast on the control shaft *m* and which has to transmit the controlling of the electrical part of the switch from one pump to another, also takes up different positions. The control 55 lever *p*, by means of the slot guide *p'*, can actuate the roller 41 of the switching rod 40.

What I claim is:

1. In a fluid supply system, a plurality of pumps, electric motors for driving said pumps, one for each pump, a circuit controlling device for each motor, and means operable upon a predetermined change in the rate of consumption of the fluid in said supply system for simultaneously closing the circuit controlling device for one of said motors and opening the circuit controlling device for another of said motors. 60

2. In a fluid supply system, a plurality of pumps, each of said pumps having a capacity differing from the capacities of the others of said pumps, electric motors for driving said pumps, one for each pump, a circuit controlling device for each motor, and means operable upon a predetermined change in the rate of consumption of the fluid in said supply system for simultaneously opening the circuit controlling device of the motor for one of said pumps and closing the circuit controlling device of the motor for another 80 of said pumps. 70

3. A fluid supply system as claimed in claim 2, in which the pump brought into operation upon change in the rate of consumption is of greater capacity than the pump 85 whose motor circuit has been interrupted when the pressure decreases, and of lesser capacity when the pressure increases. 90

4. A fluid supply system as claimed in claim 1, in combination with a hydraulic piston regulator in the supply system for operating the circuit controlling devices. 100

5. In a fluid supply system, a plurality of pumps, electric motors for driving said pumps, one for each pump, a pair of switches for one of said motors, said motor being driven only when both of said switches are closed, a switch for another of said motors, said switch being open when said first motor is being driven, and means for simultaneously closing the switch for said second motor and opening one of the switches for said first motor. 105

6. A fluid supply system as claimed in claim 5, in which the switch for said second motor is connected to the simultaneously moving switch for said first motor, and said means is provided with a projection adapted to engage a forked arm on one of said switches. 110

In witness whereof I have hereunto signed my name.

ERNST VOGEL.
